UNITED STATES PATENT OFFICE.

WILLIAM L. BEAN, OF WEST HAVEN, AND VINCENT L. JONES, OF NEW HAVEN, CONNECTICUT, ASSIGNORS TO McCLELLON LOCOMOTIVE BOILER COMPANY, OF BOSTON, MASSACHUSETTS, A CORPORATION OF MASSACHUSETTS.

FIREBOX.

Application filed October 21, 1925. Serial No. 63,877.

This invention relates to fireboxes of locomotives and the object is to provide an improved construction for a firebox of the water tube type.

5 Our invention will be more readily understood by reference to the following description of an illustrative embodiment thereof shown by way of example in the accompanying drawings, wherein:

- 10 Fig. 1 is a side elevation of a firebox;
Fig. 2 is a rear end elevation thereof but with the wall tubes omitted for clearness; and

15 Fig. 3 is a view similar to Fig. 2 showing the wall tubes but omitting the bracing.

Our invention relates to fireboxes wherein the water-containing walls are constructed of tubes as distinguished from spaced sheets and the particular form illustrated has many 20 features of similarity to the construction shown in Patent No. 1,248,856, dated Nov. 27, 1917, to James M. McClellon, and may be considered a development and improvement of the firebox disclosed in said patent.

25 Referring to the drawings, we have there shown a firebox comprising a foundation chamber 5 which may be formed of a hollow steel casting or mud ring of general U shape, the arms of the U entering a throat chamber 7, and a crown chamber which may comprise 30 a central cylindrical drum 9 and lateral drums 11, these drums having opposed flattened sides which fit together in inwardly and downwardly converging planes so that 35 the drum 9 seats between the other two in the manner of a keystone. The forward ends of the crown drums communicate with the barrel of the boiler and they may be supported adjacent their forward ends by an 40 extension 13 of the barrel shell substantially as in the patent referred to.

The side walls of the firebox may be composed of thin walled cylindrical tubes 15 set side by side substantially in contact and 45 having their ends entering and expanded in the arms of the foundation chamber 5 and the sides of drums 11. The rear wall of the firebox (see Fig. 3) may also be defined by a plurality of tubes 17, conveniently somewhat 50 smaller in section and somewhat more widely spaced than the side wall tubes, extending generally between the cross member of the foundation chamber 5 and the

crown drums. The tubes enter substantially perpendicularly the surfaces with which they connect and in the case of the crown drums this implies a radial presentation. As indicated in Fig. 3, the upper ends of some of the tubes 17 may be somewhat deflected and staggered relatively to others to 55 permit their connection to the drums 11. Provision is also made in the back wall for openings therethrough preferably in a manner which will be later described.

To support the crown and relieve the firebox tubes of any structural loads other than those occasioned by reason of their containing hot water under pressure and to provide a desirable rigidity in the firebox to resist the racking strains incident to the passage 70 of the locomotive over the road while relieving the tubes and their connections of the damaging effects of such strains, we provide for supporting the crown drums from the foundation chamber 5 independently of 75 the tubes which connect the two chambers. Referring particularly to Figs. 1 and 2, we have herein shown suitable pillars disposed at intervals around the firebox, as, for example, pillars 19 and 21 at each side and pillars 23 and 25 at the rear end. Herein the mud ring 5 may have cast integrally therewith steps or brackets 27 and to the crown drums may be secured suitable bracket-like castings 29 and 31 by means of fitted bolts. 80 The members 27, 29 and 31 as clearly shown in Fig. 2, present shoulders and lips receiving the ends of the vertical braces or pillars such as 21 and 23, relieving the bolts of 85 shearing action and preventing working of the parts. As best seen in Fig. 1, the brackets or fittings 31 at the rear end of the crown chamber may be provided with flanges 33 underriding the ends of the drums so that 90 they provide saddle-like supports therefor. 95

Referring to Fig. 2, to provide space at the rear end wall for the fire door and the like the supporting frame-work at this end may comprise the lateral pillars 23 and 25 disposed at the sides and supporting the 100 lateral drums 11 and the central drum 9 may be carried by braces 35 secured to these pillars and to a bracket 37 secured to the central drum, the function of which is similar to the brackets 31, these braces and the bracket 105 37 forming in effect an arched girder ex-

tending between the two pillars, thus leaving unobstructed a portion of the rear wall of the boiler between them.

Means are preferably provided to give 5 horizontal stiffness to the frame-work. For this purpose (see Fig. 1) the pillars 19 and 21 at the sides of the boiler may be connected by a brace 39. A brace plate 41 may extend entirely across the back end of the 10 firebox, as shown in Fig. 2, and be secured to the pillars 23 and 25, extend around the rear corners of the firebox and there be secured to the pillars 21 on either side. Referring to Fig. 2, it will be noted that this 15 plate 41 provides a tension member between the two pillars 23 and 25 supporting them as abutments against the thrust of the arch formed by the elements 35 and 37.

The frame-work described may be utilized 20 not only to relieve the water tubes of structural strains but also to support various fittings which are normally carried on the walls of the firebox. The longitudinal brace 39 along the side may, if it is desired, be 25 so located as to permit the attachment thereto of the usual steps at the exterior of the firebox while the plate 41, which is preferably constructed as shown as a wide encircling belt, may support the majority of the 30 important cab fittings or locomotive accessories which are customarily applied in the back head region of the firebox. Thus, referring to Fig. 2, the central portion of the plate may be provided with an opening 43 35 constituting a fire door opening and the fire door and the fire door screen may be carried on the plate 41 rather than on the tubes of the back head. We have also illustrated 40 openings 45 which may receive the distributor tubes of an automatic stoker, such a stoker being indicated at 46 in Fig. 1 in dotted lines. Examples of other fittings which 45 may be carried by the plate 41 are the air brake and valve control equipment, the injector fittings for the inside injector, the stoker control mechanism, miscellaneous small valves and fixtures and the holders for oil cans and tools.

Referring to Fig. 3, in the embodiment of 50 the invention shown the back head tubes 17 at the sides extend uninterrupted between the drums 11 and the foundation chamber 5. In the central part of the back wall the tubes 55 extend from the crown drum to a fire door frame which may comprise two large lateral tubes 47 connected by a header 49 to form the top of the firebox and opening at their lower ends into a box-like chamber 51 erected on the foundation chamber 5. The opening 60 defined by this structure registers with the opening 43 in the plate 41 shown in Fig. 2 and in Fig. 2 we have illustrated an opening 53 through this plate to give access to the wash-out plug 55 in the header 49.

65 To provide openings through the wall de-

fined by the rear tubes 17 to give access to the firebox space we have illustrated a construction which herein provides for the application of the stokers but which, of course, may have a different application. Referring 70 to Fig. 3, certain of the tubes 17 may be bent laterally between their ends as indicated at 57, these and adjacent tubes being suitably bent lengthwise of the boiler to permit this 75 transverse displacement to be effected in the most convenient manner. By this bending an opening through the tubular wall is defined providing access to the interior of the firebox. In the present embodiment of the invention these openings register with the 80 openings 45 in the plate 41 and since through this plate 41 provision is made for the attachment and support of the mechanism utilizing the opening through the firebox wall 85 (in this instance the automatic stoker) the provision of this opening by deflection or displacement of the tubes in the manner illustrated is most practical. It will be noted that it involves no additional joints or 90 connections and the mounting of no fittings or attachments on the tubes themselves.

We have described in detail the particular embodiment of our invention which is shown 95 by way of example in the accompanying drawings. Obviously, however, this is shown by way of illustration merely and the principles of construction exemplified thereby may be embodied in widely different mechanical forms without departing from the spirit of our invention. What we claim as new 100 and desire to secure by Letters Patent we shall express in the following claims.

Claims:

1. A locomotive firebox comprising a 105 crown chamber and a foundation chamber, a frame-work for supporting the former from the latter independently of the water-containing walls of the firebox, and walls comprising tubes extending between the chambers, said frame-work including as a part 110 thereof a plate extending across the rear wall of the firebox and providing for the support independently of the tubes of cab fittings as, for example, the fire door.

2. A locomotive firebox comprising a 115 crown chamber, a foundation chamber, walls of tubes connecting the same, opposed brackets on said chambers and pillars interposed between the brackets for supporting the crown chamber from the foundation chamber 120 independently of the tubes.

3. A locomotive firebox comprising a hollow cast-steel mud ring having an integral bracket, crown drums having brackets secured thereto, water-containing wall tubes between said ring and drums and pillars interposed between the brackets to carry the drums from the mud ring independently of the tubes.

4. A locomotive firebox of the water tube 130

type comprising a foundation chamber and a crown chamber, laterally disposed pillars at the rear of the firebox supporting the lateral portions of the crown chamber from the foundation chamber, a girder between the pillars supporting the central portion of the crown chamber and a plate connecting the pillars and providing a support for cab fittings.

10 5. A locomotive firebox comprising a foundation chamber, a crown chamber and walls of tubes, upright pillars at intervals about the sides of the firebox to support the crown chamber from the foundation chamber independently of said walls and transverse ties between said pillars.

6. In a locomotive boiler a firebox comprising a crown chamber and a foundation chamber and walls of water-containing tubes extending therebetween, said crown chamber supported at its forward end by the barrel shell, fittings at the rear end of the crown chamber having arms underriding the same and shouldered upright arms and pillars rising from the foundation chamber fitting 20 said shoulders for supporting the rear end of the crown chamber through said fittings.

In testimony whereof, we have signed our names to this specification.

WILLIAM L. BEAN.
VINCENT L. JONES.
